(57) **CLAIM**

The ornamental design for a modular lamp, as shown and described.

DESCRIPTION

FIG. 1 is a perspective view of a first embodiment of a modular lamp showing my new design;

FIG. 2 is a front elevation view thereof;

FIG. 3 is a left elevation view thereof;

FIG. 4 is a right elevation view thereof;

FIG. 5 is a rear elevation view thereof;

FIG. 6 is a top view thereof;

FIG. 7 is a bottom view thereof;

FIG. 8 is a front elevation view of a second embodiment of the modular lamp, which is substantially identical to the first embodiment, the sole difference being the number of vertically stacked rows of modular elements; and,

FIG. 9 is another front elevation view thereof, showing the modular lamp in an alternate environment of use.

The broken lines shown in the drawings illustrate environmental subject matter only and form no part of the claimed design.
